UNITED STATES PATENT OFFICE.

GLENN J. BARRETT, OF GRAND RAPIDS, MICHIGAN, ASSIGNEE, BY MESNE ASSIGNMENTS, TO BARRETT ADDING MACHINE COMPANY, OF WILMINGTON, DELAWARE, A CORPORATION OF DELAWARE.

ACTUATING DEVICE FOR KEY-SET CALCULATING-MACHINES.

1,108,118.

Specification of Letters Patent. Patented Aug. 25, 1914.

Application filed August 15, 1911. Serial No. 644,081.

To all whom it may concern:

Be it known that I, GLENN J. BARRETT, a citizen of the United States, residing at the city of Grand Rapids, county of Kent, and 5 State of Michigan, have invented certain new and useful Improvements in Actuating Devices for Key-Set Calculating-Machines, of which the following is a specification.

This invention relates to improvements in 10 actuating devices for key-set calculating machines.

The objects of this invention are to provide certain emergency devices for the elimination of errors in conjunction with the actuating handle means adapted to a key releasing device appearing in my patent application, Ser. No. 565,561, filed June 7th, 1910, and finally allowed June 7th, 1911.

The object specifically is to provide in connection with such actuating means which 20 ordinarily entirely dispense with the key button or independent release, a separate release button device which will throw the machine out of operation at any stage of its 25 manipulation prior to the actuation of the deals whereby a mistaken number may be eliminated from the count.

Further objects and objects pertaining to structural details will definitely appear from 30 the detailed description to follow.

I accomplish the objects of my invention by the devices and means described in the following specification.

The invention is clearly defined and 35 pointed out in the claims.

A structure constituting an effective and preferred embodiment of my invention is clearly illustrated in the accompanying drawing forming a part of this specification, 40 in which—

Figure I is a perspective view of a tabulating machine embodying the features of my invention taken at the right hand or handle side, the casing being omitted. Fig. 45 II is a detail view of the mechanism appearing on the left hand side of the case illustrated in Fig. I. Fig. III is a detail elevation view of the connection for the emergency key or keys and the related parts. Fig. IV is a detail of the sliding bar 62, 50 showing the stop member projection thereon. Fig. V is a detail vertical sectional view from front to rear through the body of an adding machine embodying the fea-

tures of my invention. Fig. VI is an enlarged detail perspective view of the key stem releasing slide.

In the drawing, similar numerals of reference refer to similar parts throughout the 60 several views.

I have shown my actuating devices applied to a key-set form of calculating machine. The method of actuating the dials is immaterial to my invention. The mechanism between the two side plates 1 and 2 65 may be in any form well known in the key-set adding machine art. It will be understood that this mechanism includes means for latching the keys in depressed position; means for unlatching the same during the 70 operation of the handle; an actuating means for rotating the dials, the movement of which is controlled or limited by the respective keys of the key board.

Means are provided for disengaging the 75 dials with the said dial-actuating means during the movement of the latter away from the normal position. Means are provided for maintaining said dial-actuating means in engaged relation to said dials during the 80 return of the former toward the normal position. Also a detent means is provided for engaging the dials against rotation while the latter are disengaged from the dial actuating means. The form of these various 85 mechanisms is not material to my invention. These devices for all of these purposes are well known. The specific mechanism is the same as that appearing in my aforesaid patent application, and is substantially like the 90 mechanism disclosed in my Patent No. 976,366, issued to me Nov. 22nd, 1910.

Briefly described, the various mechanisms are supported between the side plates 1 and 2. 95

78 are depressible key stems, which, when depressed, interpose stops in the path of the reciprocating members 81.

80 are the stops co-operating with the engaging portions of said key stems. 100

93 is a releasing slide which serves to release the depressed key stems during the operation of the handle in a manner disclosed in said Patent No. 976,366. Said slides are also given a rearward movement 105 upon the depression of the key stem co-operating therewith, which rearward movement elevates the catch 95 out of engaging rela-

tion with the pin 97 in the slide 81, so that when the handle is operated the particular slide whose catch is thus elevated, may go forward until engaged and stopped by the depressed key stems coöperation with said slide.

The bail arm 39 carrying the bail 41 swings on the pivoted point 86 during the operation of the handle. The connection between said bail 41 and the slide may be traced through the parts 106 and 107, 107 being carried by 106 and having a sliding movement thereon against the tension of the spring 108. 107 contacts with the slide 81 at the point 109. During the forward movement of the bail 41, the member 81 is drawn forward by virtue of the connecting spring 82 between 81 and 107, all of which movements are clearly described in my said Patent No. 976,336.

The form of the accumulating dial section shown herewith is also in general like the corresponding sections shown in my said patent. The connection between the reciprocating sliding members 81 and said dials, may be traced through the parts 83, 84, 103, 85 and the dials 87. The reciprocating members actuate said dials by virtue of said connections. The movement of lever 48 as described, locks and unlocks the dials with their respective actuators, this locking being accomplished by elevating the locking members 102, which locks the pawl 103 into the dial driving gear 85. The unlocking is accomplished by the reverse movement of 102. This locking and unlocking constitutes an engaging and disengaging of the dials from their actuators. It will be understood that during resetting of the dials to the "0" that the members 102 will be held in locking position with reference to pawl 103 until the dials are rotated backwardly to said "0" point and then afterward dropped to unlocking position. The exact form of said dial and actuating mechanism is immaterial to my invention, but a full description of the structure which I have shown in connection therewith may be had by reference to said Patent No. 976,336.

Fig. I shows a perspective view of the right side of a calculating machine embodying my invention. The handle piece 3 is mounted upon the sliding arm 4, which is held in position as shown by means of an extension of the bearing for the handle 3. The lower portion of this sliding arm 4 is pivotally attached to the auxiliary crank arm 7 on the sleeve 8 and is adapted to rock on the hub 9 which is rigidly attached to the arm 5. This hub 9 fits into the bushing 11 in the main driving sector 12, which is rigidly secured to the shaft 13. (See Fig. 2). This shaft extends through the machine and carries upon the left side thereof the secondary sector 14 and connected parts.

Attached to the main sector 12 at 33 is the main pitman 34. This, in turn, is pivoted to the arm 35 at 36. The arm 35 is pivotally mounted upon the side plate 1 at 42. At 37 is pivotally attached the connecting link 40, 70 the other end of which is attached to the pick-up arm 39 at 38. The functions of these arms fully appear in my former patent, see Fig. 3, where the bail 325 is carried by arms 350.

41 is the pick-up bail which has a reciprocatory movement and whose function is to pick up the dial actuating members and restore them to normal positions during the return movement of the actuating handle, 75 a common feature in these adding machines.

44 is a shaft extending through the machine parallel to the shaft 13. Upon the right end of this shaft is carried the lifting arm 43. When the operating handle is placed in working position, as shown in Fig. I, the finger 8' of the sleeve 8 comes under the forward portion of this lifting arm 43. When this sleeve is rocked on the hub 9, this finger 8' abuts the lifting arm 43, and causes 90 the shaft 44 to rock.

Upon the left side of the machine (see Fig. II), and upon the left end of the shaft 44 is the arm 45 with the pin 46 in a slot of the vertical sliding member 47. When 95 the operation just described takes place, this slide is forced downwardly, which in turn moves the lever 48. The function of this lever 48 is to engage and disengage the dials from their actuating members, a common 100 feature of machines of this class. The manner in which this is accomplished is not material to my invention. It will further be understood that when the rear portion of this lever 48 is depressed, as described, the 105 dials become locked with their respective actuating members by any suitable means.

As stated, the dials are engaged and disengaged from their actuators, a common feature in adding machines, by the rocking of 110 the lever 48 upon the pivotal point 49. This is fully described in detail in my said former patent. This lever is actuated by the movement of the roller 56 as it cooperates with the upper side of the lever. A 115 lever 59 pivotally mounted at 58 carries said roller 56, and upon this lever are the contact pins 57 and 60. A double acting pawl 61 mounted upon the secondary sector 120 14 is adapted to engage the pin 60 upon the forward movement of the sector 14. This throws the lever 59 into position shown in Fig. II, which, it will be understood, by reason of the coöperation with the cam on the lever 48, disengages the dials from their 125 actuating members. When the said secondary sector 14 reaches the forward limit of its movement, the under portion of said pawl 61 engages the pin 57 in such a manner that the beginning of the return movement 130

of said secondary sector 14 causes said roller 56 to force the rear portion of said lever 48 downwardly, which will be understood re-engages said dials with their actuating members.

62 is a bar having an inwardly-extending stop member 62', whose function is to prevent the pawl 61 from engaging the pin 57, as previously described, when it is desired to clear the machine. By reason of the connections from the slide 47 to this sliding member 62, which may be traced through the pin 67, the bell crank 66, the link 65, and the lever 64 pivotally mounted at 63, when the slide is depressed when clearing the dials, this bar 62 is forced rearwardly upon the grooved pin 53, which it embraces by a slot at the end. (See Figs. 3 and 5). This movement brings the ear of the projection 62' on said bar into the path of travel of the pawl 61 at the point in the movement of the latter when it would normally be in position to engage the pin 57. The point upon the under side of said pawl 61 where said projection 62' contacts with said pawl, is slightly forward of the pivotal point of said pawl 61 upon the secondary sector 14, which tilts said pawl upwardly to such an extent that the engaging portion thereof is free and clear of the pin 57; and so it will be readily seen that while said slide 47 is depressed during the operation of clearing the dials, said pawl cannot cause said dials to become reengaged with their actuating members, after having been freed therefrom by the upward movement of said slide 47 previously explained.

In general, the operation of the clearing actuating mechanism previously described is as follows: When it is desired to return the dials to the "0" point, in other words, clear the machine, before drawing the handle forward, and instead of depressing a clearing key as is usually necessary in machines of this class, the handle finger piece 3 is depressed toward the base of the machine. This movement first releases any keys in the key board which may happen to have been previously depressed, and also releases the dial actuating members so that the same may go forward, as will be explained hereinafter. These operations are fully described in my said former patent. During the movement of said handle toward normal position, it restores the dial actuators to normal position, while the same are disengaged from said dials, and the projection 62' prevents the pawl 61 from normally co-operating with said pin 57.

60 As stated, it will be understood that between the sides 1 and 2, there is mechanism for releasing the keys from depressed positions. It will be further understood that the rocking of the shaft 63, the pivotal point of the lever 64, actuates said key releasing

mechanism, the details of the latter being immaterial to my invention.

It will also be understood, that in common with other machines of its class, this machine shown in connection with my invention has a means of releasing the dial actuators when clearing the machine so that said actuators may go forward during the operation of the handle, there being no key in the key board to be depressed. Normally, the depression of any key in any column, releases the dial actuator of that particular column, as will be readily understood by those familiar with the adding machine art as applied to machines of the class shown herewith. This releasing means for the purpose of "clearing" is also controlled by the rocking of said shaft 63. These parts are all as described in my former patent application referred to, and I have numbered them exactly as they appear in my said former patent application. My present improvement is auxiliary thereto.

I connect to the rocking shaft 63 an actuating arm 120 to which I connect a key-stem 121 having a key-button 122. From this it will be seen that whenever a number of keys have been depressed and the actuating handle is started, that it will be possible in an emergency to release all of the keys by depressing the key button 122 and to prevent the sum set in the machine from being accumulated on the dials. This will allow the key stems of the keyboard to rise out of engagement so that the handle can be manipulated without accumulating the amount that is thus set in the machine. The slide bar 62 will also be actuated and perform its functions. It is not necessary that the key lever be connected directly to the shaft 63, as indicated, but a key can be connected to any other part that will actuate the shaft. A key 125 can be connected to one of the arms of the irregular lever 66. See particularly Fig. III. When this key is depressed, the same result is secured. This is of advantage as it enables the correction of mistakes. It also affords a convenient left hand button for releasing the keys after they have been set.

Having thus described my invention, what I claim as new and desire to secure by Letters Patent is:

1. In an adding machine of the class described, the combination with a dial actuating means; a dial resetting means, a plurality of keys controlling said dial actuating means, operating means, means for holding said keys depressed, releasing members for said keys, a suitably journaled rock shaft, a 125 rod secured to crank arms fixed on said rock shaft and engaging the key releasing members, means connected to said operating means for rocking said shaft, a crank arm on said shaft and a key stem secured to said 180

crank arm whereby said shaft may be independently rocked, all coacting substantially as described for the purpose specified.

2. In an adding machine of the class described, the combination with operating means, dial actuating means, a dial resetting means, a plurality of keys controlling said dial actuating means, means for holding said keys depressed, releasing members for said keys, a rock shaft suitably journaled, a rod secured to crank arms fixed on said rock shaft and engaging the key releasing members, means connected with the operating

means for rocking said shaft, and means directly connected to said operating shaft 15 for independently operating the same, all coacting substantially as described for the purpose specified.

In witness whereof, I have hereunto set my hand and seal in the presence of two witnesses.

GLENN J. BARRETT. [L.S.]
